APPARATUS AND METHOD FOR FORMING A SHEET OF INTEGRATED MICA

Moses D. Heyman, Woodmere, N. Y.

Application February 6, 1952, Serial No. 270,242

7 Claims. (Cl. 154—2.5)

This invention relates to an apparatus and method for forming a sheet of integrated mica from thinly split flakes and deals more particularly with an apparatus embodying means for utilizing flakes that may otherwise be wasted and which render difficult proper cleansing of the liquid medium in which the flakes are borne so that said medium may be re-circulated.

Reference is made to my pending application Ser. No. 201,020, filed December 15, 1950, issued as U. S. Patent No. 2,659,412. In the production of a continuous sheet of integrated mica according to said application, a material proportion of the mica flakes are so extremely fine that they settle very slowly in the liquid from which they are deposited to form a sheet. Therefore, these finer flakes remain in the upper portion of said liquid. Inasmuch as the level of the liquid in the sheet forming means must be maintained quite constant for best results, an excess of liquid is used and an overflow is employed to maintain the level. The liquid spilling through such overflow contains, in suspension, a substantial quantity of these finer mica flakes. Another source of loss of these finer flakes is in withdrawal of liquid by vacuum in means employed to effect efficient transition of the sheet being formed from immersion in the liquid to the atmosphere thereabove. These fine flakes, which would otherwise be wasted, are, in fact, those best suited to form integrated mica because they have great cohesive force and also because they provide the integrated sheet with fine-textured and smooth surfaces.

Accordingly, it is an object of the present invention to utilize as great a proportion of such otherwise wasted flakes as can be recovered and return said flakes to the sheet-forming means for incorporation into a sheet of integrated mica.

In the interests of economy and for other reasons, it is desired to re-circulate the liquid medium employed to carry the flakes. However, the mentioned thinner flakes that accompany the liquid withdrawn from the sheet-former are in such large quantity that they quickly clog any strainer or filter provided to intercept them and also render difficult the proper maintenance of operation of splitting, ionizing and pumping means, etc. employed in the preparation of the flakes before they are incorporated in an integrated sheet.

Another object of the invention, therefore, is to recover the otherwise wasted thinner flakes, as above mentioned, so that the relatively few flakes that cannot be recovered can be filtered out efficiently, thereby insuring substantial freedom from mica flakes of the re-circulating liquid and proper operation of the flake preparing and producing means.

A further object of the invention is to provide novel means for producing a sheet of integrated mica that has its outer surfaces comprised of thinner flakes than comprise the interior of the sheet.

A still further object of the invention is to provide novel and improved flake-recovering means whereby

2

only a small and immaterial percentage of the flakes introduced into the sheet-former are wasted.

My invention also comprises novel details of construction and novel combinations and arrangements of parts which will more fully appear in the course of the following description, the same having basis on the apparatus shown in the accompanying drawing which is exemplary of apparatus according to the invention.

In the drawing:

10 Fig. 1 is a systematic view, partly in section, of apparatus according to the present invention.

Fig. 2 is an enlarged cross-sectional view as taken on line 2—2 of Fig. 1.

Fig. 3 is a greatly enlarged fragmentary sectional view 15 of an integrated mica sheet as produced by said apparatus.

In the drawing there is shown a chute 5 which discharges liquid-borne mica flakes and a pipe 6 which returns the liquid discharged by said chute to the source from which the flow in said chute came. It is understood 20 that apparatus, immaterial to the present invention, is inter-connected between said chute and pipe to disintegrate pieces of mica into fine flakes or splittings and to provide a flow of liquid-borne flakes to chute 5.

The present apparatus comprises, generally, sheet-forming means 7, means 8 conducting liquid from said means 7, means 9 to recover mica flakes in the liquid flowing in means 8 and returning the same to the sheet-forming means, a settling tank 10 receiving the discharge of liquid from means 9, means 11 interposed between tank 10 and pipe 6 to strain or filter the liquid from tank 10, and means 12 to periodically flush or cleanse the filter means 11.

The sheet-forming means 7 comprises, generally, a tank 13 that is preferably provided with an upwardly sloping bottom 14, a relatively narrow transverse static head settling chamber 15 disposed intermediate the ends of tank 13 and defined between transverse walls 16, the tank being divided by chamber 15 into a deeper chamber 17 and a shallower chamber 18, and conveyor means 19

25 moving through the tank, substantially parallel to the sloping bottom thereof, and receptive of mica flakes settling downward in chambers 15, 17 and 18. The conveyor means moves in the direction of arrow 20 and said means

30 comprises a support belt or chain 21 preferably formed of articulated links or otherwise formed to be non-stretchable, and a relatively thin woven nylon web 22 for which belt 21 serves as a support. The conveyor means 19 thus provided moves through the tank 13 in an upwardly sloping direction with web 22 uppermost. Suitable pulleys 23 may be provided to guide conveyor means 19 as desired.

It will be realized that, as conveyor means 19 moves along the inside of tank 13, mica flakes in the flow discharging from chute 5 into static head chamber 15 will settle onto web 22 and, that such of the flakes that do not settle on the web in said chamber pass with the liquid into chambers 17 and 18, and that the flakes in the latter chambers also settle onto the web. It will be seen, however, that the relatively finer flakes in chamber 17 settle on the web first to form a layer 24 of such finer flakes; that as the web passes beneath chamber 15, the relatively thicker and heavier flakes therein are deposited on layer 24 to form the coarser layer 25; and that as the web moves through chamber 18, the finer flakes in the latter chamber settle on layer 25 to form the fine layer 26. Fig. 3 shows the product resulting from such successive deposit of flakes.

Means 8 comprises an overflow trough 27 positioned in tank 13 to maintain a constant level of liquid in said tank, said trough discharging, under pressure of a suction pump 28, into a pipe 29. It will be evident that such liquid contains mica flakes that are too fine to settle

rapidly and, therefore, are drawn off with the surface liquid from tank 13. Means 8 also includes vacuum means 30 disposed below web 22 where the same moves out of the liquid in tank 13 and provided to prevent wash-back of the flakes on the web. Said vacuum is created by a suction pump 31 and is effective through the interstices of the woven web to firmly hold the deposited flakes on the web as the latter breaks through the surface of the liquid. Since means 30 is partly immersed in said liquid, pump 31 draws liquid and flakes suspended therein out of the tank through a pipe 32 which joins pipe 29 to form a pipe 33 that terminates in a perforated header 34. It will be clear that the flow from the perforations 35 of said header comprises liquid and flakes and that said flakes, being removed with the top liquid, are the finer and slower settling flakes.

The flakes deposited on web 22 become an integrated sheet and said sheet is removed from the web in a manner and by means not pertinent to the present invention. In any case, the web returns to the deeper part of tank 13 to again receive deposits of mica flakes as above set forth.

The mica flake-recovering means 9 comprises, generally, a woven belt or web 36 similar to web 22 and disposed to receive the discharge of header 34, a set of concavely formed rollers 37 supporting an upwardly sloping run 38 of web 36 so as to impart a trough-like transverse sectional form to said web run, a tank 39 to receive the flow of liquid passing through the interstices of web 36, and a set of pulleys 40 over which said web is trained so that the same has a substantially vertical run 41 terminating above chamber 17.

Web run 38 is disposed at an upward slope so as to drain back into tank 37 therebeneath, the web being driven by means 42 at a desired speed to allow such drain-back without spillage over the end of said tank. As seen in Fig. 2, the concavity of the web run, as formed by rollers 37, prevents side spillage of liquid which, therefore, must drain through the web and, in the process, deposit mica flakes 43 on said web. According to the direction of arrow 44, flakes 43 are carried by web run 41 toward chamber 17. These flakes are washed from the web into chamber 17 by a nozzle 45 which receives its flushing liquid from the discharge of a pump 46 having an inlet 47 that draws water or liquid from tank 13. Such flakes that may cling to web 36 beyond the place impinged by the flushing liquid, may be dislodged or scraped off as by a doctor blade 47a to fall into chamber 17.

In the above manner, flakes removed from tank 13, in any of the ways above described, are returned to said tank, and more particularly, chamber 17, to provide a large proportion of the flakes that form sheet layer 24. In practice, some 94% of the flakes discharged from chute 5 become embodied in the integrated sheet formed by the present apparatus. The remaining 4% are so extremely small and fine as to pass through the interstices of web 36 into tank 39.

Settling tank 10, by means of a pipe 48, receives the flow from tank 39. By means of baffles or other known means within tank 10, much of the fine flakes suspended in the liquid are settled out and, from time to time, these flakes are emptied into a drain by opening normally-closed valve 49. The upper portion of the liquid in tank 10 is drawn off through a pipe 50 to the filter means 11 by means of a suction pump 51 connected in said pipe.

Filter means 11 comprises a filter or strainer 52 that receives liquid flow from pipe 50, filters out any residual fine flakes from said flow, and discharges the resultant flake-free liquid into pipe 6. Between pump 51 and the inlet to filter 52, pipe 50 is provided with a check valve 53 that prevents backflow to said pump. The outlet 54 of the filter is provided with a normally-open valve 55 and a similar, but normally-closed valve 56, is provided at

the end of the filter through which cleansing is effected. It will be clear that the flow into the filter normally reaches pipe 6 only by passing through filter unit 57 that intercepts the relatively small amount of flakes that remain in the flow. Since much of the 4% of waste flakes has been settled out in tank 10, filter 52 is able to function for a relatively long period before accumulations of flakes on filter unit 57 clog the same and impairs its liquid-passing efficiency.

The filter flushing means 12, however, is operated before a clogged condition of the filter occurs to insure continuous flow of liquid in pipe 6 as supplied from tank 13. As shown, means 12 comprises air cylinders 58 and 59 for operating the respective valves 55 and 56, an air line 60, controlled as by a solenoid-operated valve 61, to provide compressed air for operating said air cylinders, a pipe 62 from a source of compressed air, and a filter 63 to cleanse said air of contained oil or dirt. Line 60 is connected to filter outlet 54 and a check valve 64 is provided to check flow back into line 60. In practice, valve 61 is controlled by a suitable timing device 65 which periodically opens said valve to admit compressed air to air cylinders 58 and 59.

Under control of timing device 65, compressed air actuates cylinder 58 to close normally-open valve 55 and cylinder 59 to open normally-closed valve 56. Therefore, as said compressed air flows past check valve 64, the same reverse flushes filter unit 57 and the accumulation of flakes on the surface of said unit is blown out of the filter through open valve 56. Three to five seconds of such reverse flush is ordinarily sufficient to clear unit 57 of flakes. Since timing device 65 provides an automatic and periodic flushing operation, the flow to pipe 6 is maintained and the liquid flowing in said pipe is substantially clear of all flakes and quite suitable for re-circulation and re-use.

While I have described what I now regard as the preferred form of my invention, realizing that the same may be varied without departing from the spirit and scope of my invention, I desire to reserve to myself such modifications thereof that may fall within the scope of the appended claims.

Having thus described my invention, what I claim and desire to obtain by Letters Patent, is:

1. Apparatus for forming a continuous sheet of integrated mica comprising a tank provided with a static head settling chamber intermediate its ends to provide said tank with settling chambers one on each side of the static head chamber, said chambers being connected at their bottoms, a web moving through the bottoms of said three chambers and receptive of mica flakes settling downwardly in said chambers, an inlet for a flow of liquid-borne mica flakes to said static head chamber, an outlet for excess liquid in said tank and in the upper portion of the tank, means to maintain a constant level of liquid in the tank, means to elevate the liquid passing through said outlet, and a liquid-passing conveyor receptive of said elevated outlet liquid to intercept mica flakes suspended in said outlet liquid to collect said flakes and pass the outlet liquid therethrough, said conveyor having a portion disposed to convey the flakes collected thereon back to one of said side chambers.

2. Apparatus for forming a continuous sheet of integrated mica according to claim 1, and means to remove said collected flakes from the mentioned portion of the conveyor and disposed to direct said flakes into said side chamber.

3. Apparatus for forming a continuous sheet of integrated mica according to claim 1, and means to remove said collected flakes from the mentioned portion of the conveyor and disposed to direct said flakes into said side chamber, said flake-removing means comprising a nozzle to spray liquid from the tank against the conveyor to wash the flakes therefrom.

4. In integrated mica sheet-forming means, a tank,

partitions dividing said tank into three settling chambers connected at their bottoms, one of said chambers being intermediate the other two and receptive, from the top, of a flow of liquid-borne mica flakes, a web moving along the bottoms of said chambers and receptive of flakes settling downwardly in the liquid in said chamber, an overflow for the top of the liquid in said chambers, means to elevate said overflow liquid above the tank, and means to separate mica flakes from said overflow liquid and return said separated flakes to one of said other two 10 chambers.

5. In integrated mica sheet-forming means having an overflow of liquid, means to receive said overflow liquid and intercept mica flakes suspended therein, said means comprising a liquid-passing conveyor web disposed to 15 have a substantially horizontal run thereof in the path of said overflow liquid to pass said liquid and collect the mica flakes in said liquid and to have a substantially vertical run thereof directed toward the sheet-forming means, and means to remove the flakes from said latter 20 run and return the same to the sheet-forming means.

6. A method for forming an integrated sheet of mica flakes on a continuously moving surface that consists in directing a continuous flow of liquid-borne flakes above and onto said surface and to immerse the same so that the flakes settle downwardly onto said continuously moving surface, maintaining the level of the liquid above said surface substantially constant by drawing off the liquid from the top together with flakes in suspension at said 25 top while the incoming flow continues, separating the 30

flakes from the liquid thus drawn off to collect the flakes, and then returning said collected flakes to the liquid above the moving surface forward of the mentioned flow so that said latter flakes settle downwardly onto said moving surface to cover the same before the flakes from the flow reach said surface.

7. A method according to claim 6: the steps of conveying the collected flakes toward the liquid above the moving surface, and utilizing said liquid to wash said collected flakes thereinto.
